UNITED STATES PATENT OFFICE.

BROMMIE COPELAND AND FRANK WRIGHT, OF SALEM, NEW YORK.

EXTENSIBLE LATCH.

SPECIFICATION forming part of Letters Patent No. 293,424, dated February 12, 1884.

Application filed July 6, 1883. (Model.)

To all whom it may concern:

Be it known that we, BROMMIE COPELAND and FRANK WRIGHT, both of Salem, in the county of Washington and State of New York, 5 have invented a new and Improved Extensible Latch-Bolt, of which the following is a full, clear, and exact description.

The object of our invention is to provide a new and improved latch-bolt for locks, which 10 bolt can be adjusted to extend or project a greater or less distance from the edge of the lock-casing, as the circumstances may require.

The invention consists of the novel construction, hereinafter described and claimed.

Reference is to be had to the accompanying drawings, forming part of this specification, in which similar letters of reference indicate corresponding parts in all the figures.

20 Figure 1 is a longitudinal sectional elevation of a lock provided with our improved latch-bolt, showing the same in the usual position in relation to the casing. Fig. 2 is a like view, showing the bolt adapted to project a greater distance from the lock-casing.

25 Fig. 3 is a sectional plan view of the same.

The sliding latch-bolt A, held in the lock-casing B, is composed of the following three parts: The outer block, C, held in an opening 30 in the edge of the casing, and having its outer end beveled in the usual manner; a screw, D, having a head, E, at one end, and having its opposite end screwed into the third part of the bolt—namely, a tubular piece, F, provided at its end with a fork, G, between the shanks of which the nut H is held, which fork is provided at the ends of the shanks with projections J, on which the cross-piece K of the nut can act. A spiral spring, L, surrounding 35 the bolt A, is held between the inner face of the block C, and a plate, N, attached to the casing.

The beveled block C is provided with a longitudinal aperture, through which the screw D is passed, and with a countersink, O, for 40 receiving the head E of the screw, and the screw is provided with a pin, a, directly behind the block C, to prevent said block from moving longitudinally upon the said screw. A socket-casing, P, is held in the jamb Q in 45 the usual manner for receiving the beveled block C. A square rod, Q, is passed through

the nut, to the ends of which the handle-knobs of the usual construction are fastened.

The operation is as follows: Doors and their casings frequently warp considerably, and the 55 space between the edge of the door and the jamb is so great that the end of the bolt cannot catch in the casing P, and thus does not hold the door closed. As the width between the door-edge and the jamb increases gradually, it is desirable to have a bolt which can be adjusted gradually, so that it will always project from the casing a sufficient distance to catch in the casing P. If the screw D is loosened or adjusted to project a greater distance from the piece F, the block C will project a greater distance from the casing. By 60 screwing the screw D farther into the tubular piece F the block C can be adjusted to project less from the lock-casing. A key-bolt can be 65 made extensible in the same manner as the above-described latch-bolt. The block C can be removed entirely from the casing, and can be reversed, so that the lock can be used in either direction.

We do not abandon or dedicate to the public any patentable feature set forth herein and not hereinafter claimed, but reserve the right to claim the same either in a reissue of any patent that may be granted upon this application or in other applications for Letters Patent that we may make.

We are aware that a lock has heretofore been provided with a forked tumbler, with the forks of which arms on the hub of the knob-spindle are adapted to engage to operate the tumbler.

We are also aware that it is not broadly new to form a latch or bolt in two parts connected by a screw for adjusting the length of the bolt, 80 and therefore we do not claim these features, broadly.

Having thus described our invention, what we claim as new, and desire to secure by Letters Patent, is—

1. An extensible latch-bolt consisting of a block swiveled on a screw, and connected by the latter to a piece provided with a screw-threaded aperture, substantially as herein shown and described.

2. A latch-bolt consisting of a block, C, provided with a countersink, O, a screw, D, pro-

100

vided with a head, E, and means for preventing the screw from sliding in the block, and of a tubular piece, F, provided with a fork, G, substantially as herein shown and described.

5 3. The combination, with the hub H, having arms K, of the fork G, formed with projections J and plate N, and having an internally-threaded sleeve, F, the screw D, having

head E and pin a, the block C, having countersink O, and the spring L, substantially as to shown and described.

BROMMIE COPELAND.
FRANK WRIGHT.
